UNITED STATES PATENT OFFICE.

RALPH V. L. HARTLEY, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed April 28, 1924. Serial No. 709,344.

This invention relates generally to means and a method for converting mechanical impulses into electrical impulses.

It is an object of this invention to convert 5 mechanical vibrations into electrical vibrations, through the use of space discharge devices.

It is another object of the invention to provide a simple and efficient means for varying 10 the impedance of a space discharge device in accordance with mechanical vibrations.

A further object of the invention is to utilize vacuum tube apparatus for electrically 15 reproducing mechanical vibrations produced exteriorly of the tube in such manner as to set up variations in the intensity of the electrical field in the tube to thereby effect changes or impulses in the plate current which correspond to the mechanical vibrations 20 originally produced.

An embodiment of the invention may include a vacuum tube device in which the space current is subjected to variations set up therein by mechanical movements in a control 25 device mounted adjacent to the tube and on which the mechanical vibrations desired to be electrically reproduced are impressed. The control device includes a plate member external to the tube and so related to the anode of the tube as, when free to act, to neutralize or substantially neutralize the electrical field from the anode in the neighborhood of the filament. In order to control the 30 action of the outside plate on the space current, a pair of grid members is mounted between the outside plate and the tube, the grid members being movable relatively to each other in such manner as to bring the openings 35 therein alternately into and out of mutual register or alignment to thereby alternately liberate and obstruct the action of the outside plate on the electrical field within the tube. The controlling action thus produced by the 40 grid members is preferably obtained by coupling the mechanical vibrated member to one of the grid members to vibrate the same.

In the drawing a single view in partly dia- 45 grammatic and partly sectional form illus- trates an embodiment of the invention.

Referring to the drawing for a more 50 detailed description of the invention, an evacuated tube 1 is fitted with a filament 3 and an anode 5 having lead-in conductors 7, 9 and 11 sealed in the lower wall of the tube. The 55 lead-in conductors 7 and 9 of the filament are

included in a local filament circuit including a battery 13 and a rheostat 15. The lead-in conductor 11 of the anode 5 is connected to one side of an output transformer 17 and to the positive side of a battery 19 to which the filament lead-in conductor 7 is connected as at 21 in order to provide a difference of potential between the anode and the filament. It will be recognized that with the structural arrangement described a flow of electrons 60 from the negative filament 3 to the positive anode 5 will take place when the filament is heated.

In order to vary the flow of electrons from the filament to the anode 5 in accordance 65 with mechanical vibrations produced exteriorly of the tube, a control device including a plate 23 and a grid structure 25 is mounted externally to the tube in a position to cause the filament 3 to occupy a position between 70 the anode 5 and the outside plate 23. With this arrangement, and with the plate 23 connected through the conductor 26 to the negative side of the battery 19 so as to establish the plate 23 at a negative potential with respect to the filament 3, it will be seen that a condition can be attained in which the electrical field due to the outside plate 23 will, when unrestricted in its action, neutralize 75 or nullify the action of the field due to the anode and stop the flow of current in the output transformer 17.

Advantage is taken of the power of the outside plate 23 to influence the action of the anode, by interposing the grid structure 25 80 between the outside plate 23 and the tube and using the grid structure to control the action of the outside plate on the field within the tube. For this purpose the grid structure is made up of a fixed grid member 27 and a movable grid member 29 mounted in close and 85 parallel relation to the fixed grid member. The movable grid member 29 is arranged to reciprocate in its own plane to which it is confined by the bearing members 31. Movement of the grid member 29 is effected 90 through an operating connection at 33 with a vibratory diaphragm 35 and it will be seen that the openings in the movable grid member 95 will be moved into and out of alignment 100 with the openings in the stationary grid member 27 as the movable grid member is vibrated. The effect of this is to permit the outside plate 23 to function when the openings 105 in the two grid members are in mutual 110

alignment, or register, and to cut off the action on the electrical field within the tube of the field due to the outside plate when the openings are closed.

5. It will thus be seen that the mechanical vibrations of the diaphragm 35 are directly transmitted to the movable grid member 29 and that the vibrations of the movable grid member produce corresponding variations in 10 the field in the tube, such variations being reproduced in the form of impulses or changes in the current delivered by the anode 5 to the output winding.

While the structure as thus described includes all the essentials for the purpose, it has been found that the presence of a grid member 37 in the tube renders it possible to control the flow of electrons to the anode 5 with a smaller voltage on the outside plate 23 than 20 would otherwise be necessary. Also the connecting of the inside grid member 37 and the outside grid structure 25 to the battery 19 through the conductor 39 so as to produce a negative potential thereon with relation to 25 the filament, prevents the accumulation of electrons on the glass wall of the tube and thereby increases the efficiency of operation of the device.

The vibratory diaphragm may be operated 30 in any suitable manner in accordance with the use to which the device is to be put. For example, the device may be used as a sound transmitter in which case the vibratory diaphragm 35 may be actuated by sound waves 35 conveyed thereto through the receiver, 38.

What is claimed is:

1. In a device for converting mechanical vibrations into electrical vibrations, a vacuum tube, a member mounted externally to the tube, 40 means for electrically charging said member and means for controlling the effect of said member on the electrical field within the tube in accordance with mechanical vibrations set up in said member.

45. 2. In a device for converting mechanical vibrations into electrical vibrations, a vacuum tube, a member mounted externally to the tube and capable of being electrically charged, means mounted between said member and tube for varying the effect of said member on the space current of the tube, and means for controlling the effect of said first mentioned means in accordance with mechanical vibrations.

55. 3. In a device for converting mechanical vibrations into electrical vibrations, a vacuum tube, a member mounted externally to the tube and capable of being energized to affect the electrical field within the tube, movable means 60 mounted between said member and the tube for alternately cutting off the action of the member and permitting the energized member to act on the tube, and means responsive to mechanical vibrations for vibrating said 65 movable means.

4. In a device for converting mechanical vibrations into electrical vibrations, a vacuum tube, a plate mounted externally to the tube and capable of being electrically charged to affect the electrical field within the tube, a movable 70 grid member mounted between said plate and the tube for alternately cutting off the action of the plate and permitting the plate to act on the tube, and means responsive to mechanical vibrations for vibrating said movable 75 grid member.

5. In a device for converting mechanical vibrations into electrical vibrations, a vacuum tube, a plate mounted externally to and adjacent the tube and capable of being energized to affect 80 the electrical field within the tube, an apertured grid member mounted between said plate and the tube whereby the plate may act through the openings in the grid member to control the electrical field within the tube 85 and means subject to mechanical vibration for varying the effective size of the openings in the grid member to produce corresponding variations in the operation of the tube.

6. In a device for converting mechanical vibrations into electrical vibrations, a vacuum tube, a plate mounted externally to and adjacent the tube and capable of being energized to affect the electrical field within the tube, a stationary apertured grid member mounted between 90 said plate and the tube whereby the plate may act through the openings in the grid member to control the tube, a movable member mounted adjacent the stationary grid member and adapted to be moved to alternately cover and uncover the openings in the grid member, and means responsive to mechanical vibrations coupled to said movable member for operating the same.

7. In a device for converting mechanical vibrations into electrical vibrations, a vacuum tube, a plate mounted externally to and adjacent the tube and capable of being electrically charged to effect the electrical field within the tube, a stationary apertured grid member mounted 105 between said plate and the tube whereby the field due to the plate may act through the openings in the grid member to control the tube, a movable grid member mounted adjacent to the stationary grid member and adapted to be vibrated in its own plane to vary the effective size of the openings in the grid member, and means responsive to mechanical vibrations for vibrating the movable grid member.

8. In a device for converting mechanical vibrations into electrical vibrations, a vacuum tube containing an anode and a cathode, a source of current connected to the anode and the cathode in such manner as to provide a negative 110 potential on the cathode and a positive potential on the anode, a plate mounted externally to and adjacent the tube and connected to said source of current so as to have a negative potential with relation to said cathode whereby 115 120 125 130

the external plate may act to nullify the action of the anode, a stationary apertured grid member mounted between said plate and the tube whereby the plate may act through the 5 openings in the grid member to control the action of the anode, a movable grid member mounted adjacent to the stationary grid member and adapted to be vibrated in its own plane to alternately cover and uncover the 10 openings in the stationary grid member, and means responsive to mechanical vibrations for vibrating the movable grid member.

9. In a device for converting mechanical into electrical vibrations, a vacuum tube containing an anode and a cathode, a source of current connected to the anode and the cathode in such manner as to provide a negative potential on the cathode and a positive potential on the anode, a plate mounted externally 15 to and adjacent the tube and connected to said source of current so as to have a negative potential with relation to the cathode, the rel-

ative positions of the plate and the anode being such that the cathode is located therebetween, a stationary apertured grid member 25 mounted between said external plate and the tube whereby the external plate may act through the openings in the grid member to control the action of the cathode, a movable grid member mounted adjacent and parallel 30 to the stationary grid member and adapted to be vibrated in its own plane to vary the effective openings in the grid member so as to control the effect of the plate on the electrical field within the tube, means responsive to 35 mechanical vibrations for vibrating the movable grid member, and a grid member mounted in the tube between the anode and the cathode, said grid members being connected to said source of current so as to have a negative potential with relation to the cathode.

In witness whereof, I hereunto subscribe my name this 21st day of April, A. D. 1924.

RALPH V. L. HARTLEY.
